UNITED STATES PATENT OFFICE.

JOSEPH CARROLL, OF WIGAN, ENGLAND.

PULVERIZING-TOOL.

1,098,225.

Specification of Letters Patent. Patented May 26, 1914.

Application filed April 4, 1914. Serial No. 829,690.

To all whom it may concern:

Be it known that I, JOSEPH CARROLL, a subject of the King of Great Britain, residing at Wigan, in the county of Lancaster, in the Kingdom of England, have invented certain new and useful Pulverizing-Tools, of which the following is a specification.

The invention relates more particularly to a pulverizing tool which is carried by a supporting frame and is rotated from the main wheel of the machine.

An object of the invention is to provide a pulverizing tool wherein a series of helical blades may be revolved at high speed and the earth cut or pulverized into small fragments, which cutting tool is also provided with an extended head or disk against which the pulverized material is thrown by the tool.

The invention is best described by aid of the accompanying drawings, in which,

Figure 1 is a side view of my apparatus; Fig. 2, a plan; and Fig. 3, a plan looking upward of the cutter, the cover thereof, and the shaft above.

In these, A is a framework having at one end a link B, to which the horse or the hauling rope is attached, and at the other end a pair of handles C C.

D is a main shaft, and E the main axle both carried on framework A, or in the case of D of a vertical continuation of this framework.

F is a gear wheel acting on pinion G on shaft D, which gearing drives shaft D from the spur wheel F and wheel U at a greatly accelerated speed. Shaft D by sprocket gearing and chain H drives the shaft I, which by bevel gearing J operates the digging device K. The frame is supported on one side near the main shaft by adjustable stem L carrying the ordinary bearing wheel M. A further wheel N is carried on a similar adjustable stem L' near the handle. The smaller sprocket wheel O, the bevel gear J and the digger K are carried in an independent frame P having a rectangular projection Q sliding in a slot in the main frame. It is raised up and down by the spring bell crank handle R placed conveniently for the driver.

I do not claim as new the principle of raising and lowering and adjusting the height of the cutting device which is of course well known. Handle R works on a cross spindle S, and is conveniently placed above the righthand handle for the operator to work.

In place of a quadrant and spring catch, any other well known device can be used for holding the handle in place, or for raising and lowering the digging device, but I prefer handle and quadrant as the simplest. The digging device consists in a casting of extremely hard tough metal, preferably steel alloy, having numerous blades cut out of it resembling augers. There are eight shown in the drawing, but there can be any desired number, from two to eight. At the bottom it is preferably flat as shown in Fig. 1.

T T' are simple set-screw devices whereby the adjustable stems of the wheels are held in place on the framework. The front ones T can if desired be attached direct to the framework instead of being hung on the fixed axle E.

U is the driving wheel rotating on a round part of the front axle E, but the part of the axle passing through the piece of framework W and the main frame is secured so as to hold rigidly in these frames.

The mode of action is as follows:—The horse or hauling rope being placed in position, and attached, and the bearing wheels adjusted to the requisite heights, namely wheel M to the height of the unplowed ground and N to the depth of the cut, the machine is slowly drawn forward. The wheel U being serrated, takes a firm hold of the ground and revolves, turning with it the spur wheel F, and thus through pinion G the sprocket gear H. This turns the axle I by means of sprocket wheel O, and this in turn works the bevel gear J, and consequently revolves at considerable speed the cutter K. This cutter slices the ground into extremely thin slices, and at the same time throws them up as a sort of dust against the cover X when they again fall down on to the ground. In this way the worms and insects and other vermin are killed at the same time. In my experimental machine, the slices were about thirty to the foot, or about three-eighths of an inch wide. Slices of this thickness appear to be much more easily cut by the cutter revolving rapidly, than a slab of earth could be cut and turned over by the ordinary plow, as the cutters work something like a milling cutter on a lathe, only with this difference—that the work is fed to the milling cutter, whereas the cutter is fed to the work in my pulverizer.

If the cover of the pulverizing tool has a sharp edge, it frequently cuts hori-

zontally, the thin slice of soil coming out over the top of the cutter, and so still further pulverizes the soil, but without sending it into the bearings or wheels. I prefer 5 the cutter to stand vertically but in very stony or rough ground, I may arrange it in a sloping position so that if it comes against a rock, tree root or the like which it can not disturb or cut through, it 10 will ride over it, the frame being light enough for this purpose. This however would only be requisite as a rule in colonies and abroad, as most English fields are sufficiently clear of stones and the like. In 15 order to enable the main wheel to have a sufficient grip on the earth it is shown roughened, and it may be toothed or spiked.

I declare that what I claim is:—

1. A pulverizing machine including in 20 combination a supporting frame, a rotary pulverizing tool carried by said frame and

comprising a horizontal disk-shaped head and a downwardly projecting member carried by said head and having a plurality of cutting blades, said head extending beyond 25 said cutting blades.

2. A pulverizing machine including in combination a supporting frame, a rotary pulverizing tool carried by said frame and comprising a horizontal disk-shaped head and a downwardly projecting member carried by said head and having a plurality of helical blades, said head extending beyond 30 said cutting blades.

In witness whereof, I have hereunto 35 signed my name this 28th day of March 1914, in the presence of two subscribing witnesses.

JOSEPH CARROLL.
